ORTHOPEDIC APPARATUS

Walter D. Lang Ford, Culiacan, Sinaloa, Mexico

Original application August 5, 1937, Serial No. 157,624. Divided and this application February 14, 1939, Serial No. 256,368

2 Claims. (Cl. 128—71)

This invention relates to orthopedic apparatus and is a divisional application of my application of the same title filed August 5, 1937, Serial No. 157,624, and has for an object to provide novel means for most effectively manipulating the limbs of a patient to flex and stretch the muscles so that deformed bones may assume the positions nature intended them to.

A further object is to provide novel jaws which may be adjusted to comfortably receive the foot of a patient and squeeze the foot as in a mouth, to reshape the foot, as for instance, a club foot, and stretch the ligaments and tissue surrounding the bones in order that the operator may return the bones to normal position.

A further object is to provide a device of this character which will be formed of a few strong simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawing forming part 30 of this specification,

Figure 1 is a side elevation of orthopedic apparatus constructed in accordance with the invention.

Figure 2 is a fragmentary top plan view of the apparatus shown in Figure 1.

Figure 3 is a longitudinal sectional view through the compression jaws and showing the means for adjusting the same.

Figure 4 is an end elevation of the parts shown 40 in Figure 3.

Referring now to the drawing in which like characters of reference designate similar parts in the various views, 10 designates a main frame preferably formed of angle iron, the same having angle iron legs 11. A seat frame designated in general by the numeral 12 is supported by the legs above the top of the main frame, as best shown in Figure 1. A seat 13 is supported by the seat frame and an inclined back rest 14 is pivotally mounted as shown at 15 on the seat and is adjustably mounted to rock in any desired angular position with respect to the seat, there being a slotted segment 16 carried by the seat and a set screw 17 carried by the back rest 50 to permit of this adjustment.

A pair of jaws 18 and 19, shown best in Figure 3, is supported upon the front legs of the main frame by angle iron brackets 20 and by rods 21, best shown in Figures 1 and 2. The jaws are hollow casings each provided in the top with a padded concave depression 22 to receive the free leg of the patient when one of the legs is being operated upon. The jaws are provided in their confronting inner side walls with concave depressions 23 which are provided with respective pads 24 that are pivoted at one end to the bottom of the depression. At the free end each pad is swivelly connected to a screw 25 which is screw threadedly engaged through a bracket 26, best shown in Figure 3. The screws project beyond the outer end walls of the jaws and each are provided with a respective button 27. By turning the screws manually the pads may be enclosed upon the patient's foot for compression purposes during the corrective treatment.

One of the jaws is provided with a bracket 28 and a shaft 29 is swivelly passed through the bracket and is equipped on opposite sides of the bracket with stop collars 30. The shaft projects through the outer end wall of one of the jaws and is equipped with a crank handle 31 for rotating the shaft. The shaft passes loosely through openings 32 formed in the inner confronting end walls of the jaws and is screw threadedly engaged in an opening 33 formed in the beforementioned bracket 26. The shaft forms means for moving the jaws endwise relatively to each other to properly position the jaws for compressing the foot while the free leg is supported in one of the padded depressions 22. By referring now to Figure 1 it will be seen that back of each jaw a stationary rod 34 is secured at its ends in one of the legs 11 and in an angle iron bracket 35. A rod 36 is slidably passed through a bracket 37 which depends from the top wall of the jaw at the depression 22. The rear end of the rod is provided with an eye 38 which encircles the rod 34. The front end of the rod is equipped with a wing nut 39, best shown in Figures 1 and 2. Either of the jaws, 18 or 19, may be locked stationary in a predetermined position transversely of the supporting frame by screwing up tight its wing nut 39. Thereupon when the crank handle 31 is turned the other jaw will be moved toward or away from the stationary jaw according to the direction of rotation of the crank handle.

In the operation of the device the patient may be placed upon the seat and the seat adjusted by manipulation of the adjusting mechanism to 55

comfortably dispose the patient with one leg resting in one of the padded depressions 22 of the jaws. To apply corrective compression the foot of the patient is thrust into the foot receiving concave walls 23 of the jaws 18 and 19 and thereupon the shafts 25 are manipulated to compress the foot at the ankle.

By slight and gentle pressure of the jaws on the deformed or dislocated bones of the foot or ankle, increased little by little, and simultaneous manipulation and massaging with the fingers of the operator's hand, the tissues, ligaments and tendons are stimulated, and those adhered to the bones are loosened thus enabling the operator to more easily place each bone in its normal position. The treatments may be continued for from twenty to thirty minutes each, for days, weeks and months depending upon the age of the patient and the former care of the foot, until the deformed part is restored to normal condition. In some cases special pads are placed in the jaws to apply pressure at predetermined localized points to obtain the compression or pressure desired at these points during treatment.

From the above description it is thought that the construction and operation of the invention will be fully understood without further explanation.

What is claimed is:

1. Orthopedic apparatus comprising a frame, a seat adjustably mounted on the frame, compression jaws, means for adjustably mounting the compression jaws to move transversely of the frame, pivoted compression pads carried by the jaws, and means for closing the compression pads upon the patient's foot.

2. Orthopedic apparatus comprising a frame, a seat adjustable longitudinally of the frame, compression jaws adjustable transversely of the frame, said jaws being hollow, both jaws having limb receiving depressions in the top faces thereof, said jaws having confronting inner working faces provided with coacting foot receiving depressions, and compression pads in the last named depressions adapted to be closed upon the patient's foot.

WALTER D. LANG FORD. 25
